FACING FOR CONCRETE BUILDING BLOCKS

Scott Brobst, 433 E. Center St., Nazareth, Pa.

Filed Dec. 20, 1957, Ser. No. 704,049

1 Claim. (Cl. 50—193)

This invention relates to facing for concrete or cinder blocks in the construction of walls or buildings, the primary object of the invention being to provide a facing for the surfaces of walls which will completely cover usually unattractive surfaces of concrete or cinder blocks, to lend beauty to the wall surfaces constructed with such blocks and provide a wall of pleasing appearance.

An important object of the invention is to provide a wall covering embodying a plurality of units constructed of sheet metal or plastic material and formed with overlapping ends simulating shingles, weather boarding or the like when properly attached to a wall surface.

Still another object of the invention is to provide wall facing sections having flanges adapted to fit between adjacent blocks of building or wall structure, providing an exceptionally rigid wall.

A further object of the invention is to provide a wall facing that will not only enhance the appearance of the wall, but one which will insulate the wall against heat and cold.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawings:

Figure 1 is a fragmentary perspective view illustrating a corner of a wall structure on which the facing sections are secured, in accordance with the invention.

Fig. 2 is a perspective view of one of the surface plates used when blocks are laid from right to left away from a corner.

Fig. 3 is a perspective view of a similar surface plate used when blocks are laid from left to right away from a corner.

Fig. 4 is a perspective view of one of the surface plates used to cover half a block being laid from left to right.

Fig. 5 is a perspective view illustrating the inner surface of a corner surfacing plate.

Fig. 6 is a perspective view illustrating the inner surface of a surface plate employed at a point intermediate the ends of a wall.

Fig. 7 is a perspective view illustrating the inner surface of a surface plate corresponding to the plate shown by Fig. 4 and used to cover half a block being laid from right to left.

Fig. 8 is a fragmental sectional view taken on line 8—8 of Fig. 1.

Fig. 9 is a sectional view taken on line 9—9 of Fig. 6.

Fig. 10 is a longitudinal sectional view taken on line 10—10 of Fig. 6.

Fig. 11 is a sectional view taken on line 11—11 of Fig. 1.

Fig. 12 is a sectional view taken on line 12—12 of Fig. 1.

2

Fig. 13 is a sectional view taken on line 13—13 of Fig. 1.

Referring to the drawings in detail, the various face strip sections are better shown by sheet 2 of the drawings, 5 in which a facing strip used in facing portions of the horizontal runs or layers of blocks in the formation of a wall, are indicated by the reference character A, and as shown these facing sections are each provided with a laterally extended longitudinally disposed upper flange 10 5, terminating in a downwardly extended flange 6.

These downwardly extended flanges 6 of the facing strips A are of lengths so that their lower ends terminate in spaced relation with the lower edge of the block over which the facing strip is positioned.

Facing strips C are provided with longitudinal laterally extended flanges 7 and downwardly directed laterally extended flanges 8 which also terminate in spaced relation with the lower edge of the facing strip C. Each corner facing section D, better shown by Fig. 5 of the drawings, 20 comprises a length of ornamental sheet material bent at right angles intermediate the ends thereof, the upper marginal edges thereof being extended laterally providing flanges 8', the adjacent inner ends of the flanges 8' being cut away providing a space 9.

25 Since the corner sections D have side plates that are of a length to cover only one-half of the length of the block on which the sections D are positioned, short side sections B are provided, each section B having an upper laterally extended flange 10, and a laterally extended end 30 flange 11, the flange 11 terminating short of the lower edge of the section as shown by Fig. 4 of the drawings, to permit the section to overlap the upper edge of the adjacent lower building block.

It will, of course, be understood that the facing strips 35 as shown by Fig. 4, are used in facing a wall at the right of a corner while the facing strips that are used in facing the wall surface at the left of the corner are slightly different, as shown by Fig. 7, in that the end flange 12 corresponding to the end flange 11 of Fig. 4, is formed 40 along the opposite end of said facing strip, the flange 13, however, being identical with the flange 10 of the facing strip shown in Fig. 4.

Facing strip sections E are also provided and used in facing a wall wherein the facing sections A are used, the 45 facing strips E having a laterally extended flange 14 formed along one longitudinal edge thereof and a substantially short laterally extended flange 15 extended at right angles to said flange 14, and spaced from the end of the strips, providing an extension on said strips E 50 adapted to fit between adjacent ends of building blocks and anchored in place by the mortar placed between the building blocks, for holding the building blocks and facing strips in place.

Here it might be stated that these facing strips E 55 provide an extension 16 at one end thereof adapted to overlap the adjacent ends of wall blocks that occur at a point intermediate the ends of the various rows of blocks of a wall.

In order that the facing strips will be securely held in 60 position, the various flanges are formed with openings 17 providing pockets for the reception of mortar placed between adjacent bricks or building blocks in the construction of building walls, and between which building blocks the various flanges of the facing strips are inserted 65 holding the facing strips in place.

Having thus described the invention, what is claimed is:

A wall comprising, in combination, wall blocks laid in courses forming a building wall and secured together by mortar, and a wall facing comprising a plurality of 70 ornamental metal facing strips positioned over the outer faces of said building blocks, said strips have a greater frontal area than said outer faces of said blocks and

cover said outer faces, the ends of adjacent strips overlapping in the formation of an ornamental surface, and a vertical and a horizontal laterally extended flange formed on one vertical and one horizontal edge respectively of each of said facing strips and the length of said vertical flange being less than the length of the corresponding edge, said flanges being embedded within the mortar between the adjacent building blocks securing said wall facing strips in position, said flanges having openings

formed therein providing pockets for the reception of mortar positioned between the adjacent surfaces of said wall blocks.
